ARCH SUPPORT

Application filed March 22, 1930. Serial No. 438,080.

My invention relates to supports, more particularly to supports for supporting the arches of the human foot and consists in the combinations, arrangements and constructions herein shown and described.

Numerous attempts have been made to provide an arch support which will flexibly support the arch of the foot and which will not wear out or be crushed easily by the foot of the wearer. Many materials have been used in these attempts to provide such an arch support, such as, metal, leather and rubber. In the use of metal or other similar material for providing the flexibility of the support, it has been found that the edges of the same when arched sufficiently to flex under the weight of the foot engage the shank portion of the shoe in which the support is positioned and by constantly flexing backward and forward thereon acquire a sharp edge which cuts into said shank with consequent rapid deterioration thereof. Also in these cases where metal or other similar material is used for providing the flexible arched support it has been found that the continued flexing and unflexing of said metal part or other rigid portion for providing strength for the support breaks this metal or other similar material or reduces its flexibility with a consequent loss of resiliency in its operation. In cases where the rubber or leather alone have been used the weight of the wearer has crushed said rubber or leather and often transmitted the forces caused by the weight of the wearer to the shank of the shoe in such a manner that such shank has been broken. It is, therefore, a primary object of my invention to provide an arch support which utilizes the good qualities of both metal and softer materials, such as, rubber and leather, to provide an arch support that will flexibly and adjustably support the arches of the wearer and at the same time have sufficient strength to support the weight of said wearer, that will not cut, wear or otherwise deteriorate the shank or other portion of the shoe and will not subject the parts made of metal or other similar material to such forces and strains caused by flexing and unflexing

of said parts that the same will be broken or otherwise hampered in their efficiency.

In the use of metal and other similar materials for the construction of the support, the tender nerve and blood centers of the arch when in what is known as a "falling" condition cannot stand contact against the hard surface. For this reason arch supports so constructed must be lowered to such a degree that little support for the correction of the defective arch condition is supplied. It is, therefore, a further object of my invention to provide a device of the type described in which the use of a varied amount of resilient material is provided for easy contact with the arch of the foot of the wearer making it possible to set the arch higher without discomfort, thus providing an automatic upward massaging effect to the afflicted portion of the arch, which makes for quicker correction and restoration of the arch to its normal condition, and which further adapts the device to the weight of the user.

A further object of my invention is to provide a device of the type described which has few parts, is simple to manufacture and does not get out of order easily.

Other objects and advantages will appear as the specification proceeds and the invention will be more particularly defined in the appended claims.

My device is illustrated in the accompanying drawings forming a part of this application, in which:

Figure 1 is a top plan view of the device, 85

Figure 2 is a bottom plan view of the device,

Figure 3 is an elevational view of the device,

Figure 4 is a sectional view on line 4-4 90 of Figure 2, and

Figure 5 is a sectional view on line 5-5 of Figure 2.

In carrying out my invention, I make use of an element 1 which I term the shank engaging element, which is formed to closely and snugly engage the shank of a shoe with no greater arching of this portion than necessary to so engage said shank. This element may be formed of metal or any other material 100

suitable to provide a stiff, rigid and strong member. It is designed to furnish the main support of the remaining portions of the arch support. This shank engaging member 1 may be secured to said shank member if desired by any suitable means, such as, 5 nails engageable therethrough or any other suitable means not shown.

For lending strength to the shank engaging member, as well as providing an air 10 pocket between said shank engaging member and the shank of the shoe, the shank engaging element 1 is provided with a rib struck upwardly therein and providing a protuberance 15 3 on the upper surface and a depression or pocket 4 on the lower surface thereof. As shown most clearly in Figure 2 this rib is at the transverse center of the shank engaging element and runs substantially throughout 20 the arch portion 5 thereof. As will be most clear from an examination of Figure 3, the portions 6 and 7 of this element 1 adjacent the arch portion 5 extend substantially horizontal, thus providing smooth surfaces for 25 engagement with the shank portion with no downwardly extending sharp edges which would cut or otherwise mutilate the shank portion, during the flexing and unflexing of the element 1 during operation. It will also 30 be evident that the element 1 extends substantially over the entire width of the shank portion of the shoe in which it is mounted, thereby providing an even distribution of the 35 force exerted by the weight of the wearer through this element 1 onto the shank portion of the shoe.

For engagement with the foot of the wearer, the element 8 which I term the arch engaging element is provided. This element 10 is made of leather or any similar or other suitable material and is formed to snugly engage 40 the arch of the foot of the wearer. This element 8 is of greater extent than the element 1, thus covering said element 1 and protecting 45 the foot of the wearer from any contact therewith and from consequent injury which might be incurred by said contact.

To flexibly and resiliently support the arch, I secure between the elements 1 and 8 50 a cushioning member 9 which may be formed of rubber, or any similar or suitable material. This member 9 extends substantially throughout the length and breadth of the element 1, thereby assuring a smooth cushioning 55 of the element 8 on said element 1. It may be secured to either said element 1, the element 8 or left unsecured, as desired. In this embodiment, I show this cushioning means glued or otherwise suitably connected 60 to the member 8.

My device is equipped to vary the amount of the cushioning force existing between elements 1 and 8 by utilizing any desired number of auxiliary cushioning pads or elements, 65 such as that shown at 10 between the elements

1 and 8 or as shown between the elements 1 and 9. It is easily seen that the insertion and removal of these auxiliary pads augments or decreases the resiliency offered by the element 8 to the foot of the wearer. These members 10 as shown most clearly in Figure 5 engage with the rib 3 in what is substantially a slot and tongue joint and are thereby guided or secured in position during the flexing and unflexing movements of the various parts. 70

For permitting the ready insertion and removal of the auxiliary cushioning elements 10 between the elements 1 and 8 or the elements 1 and 9 said elements 1 and 8 are fixedly secured at only one end, in this case, the rear end as indicated at 11. This connection may consist of any desired or suitable means but is shown as comprising a rivet 12 engageable through the elements 8 and 1. This rivet 12 80 can also be engaged through the cushioning member 9 to further secure the same to the element 8 if desired. It is obvious that this form of connection permits the member 8 to be hinged about the connection 11 away from 85 the element 1 when the opposite ends of the elements 1 and 8 are disconnected. 90

The opposite or forward ends of the elements 1 and 8 and the element 9, if desired, may be releasably affixed to one another by 95 any suitable means. In this form of the invention, I show a simple latch means comprising a slotted portion 13 in the element 1 having an enlarged portion 14 and a reduced portion 15. This slotted portion 13 is adapted 100 for the reception through the enlarged portion 14 thereof of a stud 16 consisting in the device shown as a rivet engageable through the element 8 and the element 9 if desired. 105

As appears in Figure 4 this stud or projecting member 16 has a head portion 17 thereon which is of sufficiently small diameter to pass through the enlarged portion 14 of the slotted portion 13 but is of a size too great to pass 110 through the reduced portion 15 thereof. This head portion 17 engages the parts of the undersurface of the element 1 adjacent the reduced portion 15 of the slot for limiting upward movement of said stud relative to the member 1. The undersurface of the element 1 may be undercut adjacent this slotted portion 13 to engage the head 17 so that the same will rest in a position substantially flush with the bottom surface of said element 1, thus 115 providing for a smooth engagement of said surface with the shank portion of the shoe. The reduced portion 15 of the slotted part 13 is elongated as shown in Figure 2 to provide for the reception of the stud 16 therein 120 upon the flexing and unflexing of the member 8 relative to the part 1. 125

From the foregoing description, the use and operation of my device is easily understood. The operator decides upon the 130

amount of resiliency desired and inserts between the elements 1 and 8 or 1 and 9 the number of auxiliary pads 10 necessary. If he desires no more resilient cushioning than is supplied by the element 9, the insertion of the auxiliary pad 10 may be dispensed with. He then inserts the stud 16 through the enlarged portion 14 of the slot 13 until the head 17 of said stud 16 projects below the apertured portion 14 and is in a substantial plane with the undersurface of the element 1. He then presses on the element 8 or otherwise forces the stud 16 forwardly in the slot 13 into the reduced portion 15 of said slot. The entire device is then inserted in the shoe with the undersurface of the element 1 engaging the shank portion of said shoe, and secured to said shank portion by fasteners or other suitable means, which in 20 the device shown may engage through the apertures 18. Thus positioned, the device is set up for operation.

During the flexing and unflexing movements of the member 8 or the members 8 and 9, the stud 16 as heretofore set forth will reciprocate in the slot 13, thus preventing any strain which might cause deterioration and loosening of the fixed fastening means 11 or other fastening means which might be utilized. The portions 6 and 7 of the element 1, because of their broad flat surfaces 19 and 20 respectively will evenly distribute the weight of the wearer without cutting or otherwise mutilating the shank or other portion of the shoe supporting said parts.

When desired the operator has only to remove the stud from the slot 13 to permit ready access to the space between the elements 1 and 8 to add to or subtract from the amount 40 of resilient material between said elements.

It is thus seen that I have provided an arch support which utilizes metal or other rigid material to furnish the main support, to re-inforce the shank and to take up the 45 wear incident to slippage between the arch support and the shank portion of the shoe, and which further so shapes the metal member that it snugly engages the shank and does not flex relative thereto with consequent decrease in flexibility in the member and possible breakage thereof.

It is also seen that I have provided an arch support which, though it utilizes metal or other similar rigid material to furnish the 55 main support of the arch, further provides a resilient means for taking up the flexing and unflexing movements imparted to the arch support by the arch of the wearer.

It can also further be easily seen that I 60 have provided a device of the type described which is easily adjustable as regards the amount of cushioning offered thereby to the arch of the wearer.

What is claimed is:—

65 1. An arch support comprising a substan-

tially flat rigid member for engagement with the shank of a shoe, a substantially flexible member for engagement with the foot of a wearer, a cushioning member interposed between said two first named members, said two first named members having a hinged connection at one of their ends, and a releasable connection at the other of their ends for the ready insertion and removal of said cushioning member, said releasable connection comprising a slotted portion in one of said members and a projecting stud in the other of said members for engagement with said slot.

2. An arch support comprising a substantially flat rigid member for engagement with the shank of a shoe, a substantially flexible member for engagement with the foot of a wearer, and cushioning means interposed between said two first named members, said two first named members being hingedly related at one of their ends and having a slot and tongue connection at the other of their ends for the ready insertion and removal of said cushioning member, the slot of said connection having an enlarged and a reduced portion and the tongue of said connection having a head engageable through said enlarged portion and with the walls of the member having the slot adjacent said reduced portion for securing said tongue in said slot.
